US0D1047930S

(12) **United States Design Patent** (10) **Patent No.:** **US D1,047,930 S**
(45) **Date of Patent:** **** Oct. 22, 2024**

(54) **SWITCH PLATE**

(71) Applicant: **Buster and Punch Limited**, Stamford (GB)

(72) Inventors: **Massimo Minale**, London (GB); **Iain Dulley**, Winchester (GB)

(73) Assignee: **Buster and Punch Limited**, Stamford (GB)

(**) Term: **15 Years**

(21) Appl. No.: **29/915,559**

(22) Filed: **Nov. 1, 2023**

Related U.S. Application Data

(63) Continuation-in-part of application No. 29/876,409, filed on May 22, 2023, now Pat. No. Des. 1,021,813, (Continued)

(30) **Foreign Application Priority Data**

(57) **CLAIM**

The ornamental design for a switch plate, as shown and described.

DESCRIPTION

FIG. 1 is a front isometric view of a switch plate showing the design.

FIG. 2 is a front elevation view thereof.

FIG. 3 is a side elevation view thereof.

FIG. 4 is an opposite side elevation view thereof.

FIG. 5 is a top plan view thereof; and,

FIG. 6 is a bottom plan view thereof.

The broken lines in the drawings illustrate portions of the switch plate that form no part of the claimed design.

1 Claim, 6 Drawing Sheets

Related U.S. Application Data

which is a continuation of application No. 29/745, 678, filed on Aug. 7, 2020, now Pat. No. Des. 991,190.
